BOWLING GAME

Russell D. Lund, Chicago, Ill.

Application May 3, 1947, Serial No. 745,691

4 Claims. (Cl. 273—39)

1

This invention relates to a bowling game.

Specifically the invention deals with a generally U-shaped bowling game which may approximate a standard bowling alley in size, may be constructed of smaller sizes for use in home recreational rooms, or may be constructed as a toy.

According to this invention a generally U-shaped alley is provided which combines the advantages of the U-shaped and straight alleys. Because the game is formed in a U-shape, the player may easily set up his own pins, the game requires less than half the length of an ordinary standard alley, and more skill is required to make a good score, thus prolonging interest by making possible a greater range of improvement. The alley comprises a straight flat primary lane and a straight flat secondary lane connected by a curved bowl-shaped lane or bight portion so formed as to bank a ball thrown at normal speed on the primary lane into the same alley position in the secondary lane, and to confine a very fast ball within the alley. Thus a "straight ball" thrown down the center of the primary lane or a "hook ball" that moves to the center of this lane as it approaches the curved portion will maintain center position after it rounds the curve. The secondary lane and about the second half of the curved or bight portion of the alley are formed with channels which function analogously to the gutters in straight alleys. No gutters are provided on approximately the first half of the alley, including the entire length of the primary lane and the adjacent portion of the curved lane, thus permitting free play and greater accuracy in directing the ball along the alley. The gutter on the high side of the curved portion is shaped to retain the ball therein even when the centrifugal force component acting on the ball is low enough to permit the ball to roll down the embankment. Thus, once the ball enters a gutter, it will remain there.

It is, then, an object of this invention to provide a bowling game which combines the advantages of the U-shaped and straight alleys in affording a U-shaped alley and which permits of an accurate, consistent, and interesting game.

A further object of the invention is to provide a U-shaped alley having gutters which function analogously to those of a straight alley.

A still further object of the invention is to provide a bowling alley with a gutterless primary lane.

A specific object of this invention is to provide a bowling alley with straight flat primary and secondary lanes connected by a banked seg-

2

mental circular lane having ball retaining walls capable of holding a ball within the confines of the alley irrespective of the speed of the ball.

A further object of the invention is to provide a bowling game which requires more skill than regular bowling by placing a premium not only on consistent direction, but also on uniform speed of delivery, while still maintaining the game as purely a matter of skill.

10 Other and further objects of the invention will be apparent to those skilled in the art from the following detailed description of the annexed drawings which disclose a preferred embodiment of the present invention.

15 On the drawings:

Figure 1 is a plan view of the bowling game embodying the features of my invention.

Figure 2 is an enlarged sectional view taken substantially along the line II—II of Figure 1.

20 Figure 3 is an enlarged transverse cross-sectional view taken along the line III—III of Figure 1, and

Figure 4 is an enlarged transverse cross-sectional view taken along the line IV—IV of Figure 1.

25 As shown on the drawings:

The bowling alley construction 10 of my invention is of a generally U-shape and comprises a flat straight first lane 11, a flat straight second lane 12, and an intermediate banked curved lane portion 13. The bowling game construction may be of any size, but will be described as approximating a standard bowling alley in size.

In bowling, a ball would be thrown from in front of the primary lane 11, the ball being directed down the lane 11 and rolling around the banked curved portion 13 and down the secondary lane 12 toward pins 14. Scoring for the U-shaped bowling alley may be on the same basis as that

30 recommended by the American Bowling Congress, and alleys, pins, and balls may be of the same proportion and size as those recommended by the American Bowling Congress. The end of the secondary lane may be provided with the standard bowling alley equipment for setting up pins, racking pins, stooping balls, and returning balls

35 (not shown). The U-shaped bowling game may also be equipped with mirrors, lights, or other guides to assist bowlers in aiming at the pins if such is desired.

The primary lane 11 is equipped with an inside flange 15 for insuring that the ball will not leave the alley. The outside of the lane 11 has an overhanging lip 16 which will be effective to 40 maintain any ball, regardless of speed, within the

alley. The flange 15 and lip 16 extend along the inside and outside of the alley, respectively, along its entire length. As seen in Figure 1, the lip 16 becomes more pronounced gradually as it extends around the curve and an opposed ball receiving groove or channel 17 is gradually formed therebelow to provide a gutter at the outside of the alley. As seen in Figure 1, an inside groove or channel 18 is gradually formed during the second half of the curve to provide a second gutter for the ball.

Thus while the primary lane does not have gutters, the second lane is provided therewith and these gutters function analogously to the gutters in a straight bowling alley. Omitting gutters in the primary lane permits free play and greater accuracy in directing the ball along the primary lane. If the ball is directed with too much speed, it will be apparent that the outside gutter 17 will receive the ball and the ball will be guided to the outside of the pins and no score will be made. Similarly, if the ball is directed with too little force, the ball will roll into the gutter 18 and be directed therealong on the inside of the pins 14, resulting in a zero score.

The curved portion is designed so as to tend to maintain the alley position of a ball thrown at normal speed. It is so formed that a very fast ball will be confined within the alley, as will a very slow ball. The curve is preferably so designed that a "straight ball" thrown down the center of the alley or a "hook ball" that moves to the center of the primary lane as it approaches the curved portion will maintain the center position after it rounds the curve.

The alley may be surfaced with wood, metal, composition, or similar material as generally indicated by reference numeral 19; and the curved portion may be reinforced with concrete or structural bracing.

A foul line may be provided as for instance at 20. The straight primary and secondary lanes are shown to be of equal length; however, this is not essential and is merely for the convenience of a player who wishes to set up his own pins and for achieving a minimum length for the game 10. The primary and secondary lanes may be parallel and separated by a distance of from one to four times the width of either the primary or the secondary lane. The curved portion of the alley is preferably wider than the primary or secondary lane to allow for the momentum of the ball. The surfaces of the primary and secondary lanes may have the same width, while the secondary lane is provided with channels or gutters in addition thereto. The primary and secondary lanes are preferably flat and horizontal over the major part of the surface.

It will thus be apparent that I have provided a bowling game which combines the advantages of the U-shaped and straight alleys in affording the convenience and compactness of the U-shaped alleys while maintaining the features of a straight alley, such as accuracy, consistency, and interest afforded by a game, success in which is dependent almost solely upon the skill of the player.

It will, of course, be understood that various details of construction may be varied within a wide range without departing from the principles of this invention and it is, therefore, not the

purpose to limit the patent granted hereon otherwise than necessitated by the scope of the appended claims.

I claim as my invention:

- 5 1. A bowling game comprising a generally U-shaped alley including a pair of flat horizontal lanes and a banked curved lane, an inside flange extending along the inner periphery of the U-shaped alley arranged to receive and retain bowl-
10 ing balls therein; an outer lip overhanging and extending along the outer peripheral portion of the U-shaped alley for maintaining balls therein, the inner wall of said outer peripheral portion gradually forming into a channel gutter as it
15 progresses about the upper edge of the banked curved portion of the alley and along one horizontal lane thereof and cooperating with said overhanging lip to receive and retain a ball therein.

20 2. A bowling game comprising a generally U-shaped alley including a pair of flat horizontal lanes and a banked curved lane; an inside flange extending along the inner periphery of the U-shaped alley for maintaining bowling balls therein,
25 in, an outer overhanging lip extending along the outer peripheral portion of the U-shaped alley for maintaining bowling balls therein, an outside gutter extending below a portion of said lip and gradually deepening as it progresses about the
30 upper edge of the banked curved portion of the alley to extend along one horizontal lane thereof and cooperating with said lip for retaining a bowling ball therein even when the ball slows down; and an inner gutter gradually deepening
35 on the inside of the U-shaped lane at the curved portion thereof and extending parallel to said outside gutter along said one horizontal lane.

3. A bowling alley comprising flat straight primary and secondary alleys extending in spaced side-by-side relation, a banked segmental circular alley connecting said primary and secondary alleys, said banked alley having a high outer side equipped with a gradually deepening gutter and a gradually widening overhanging lip, and said gutter extending under a portion only of said lip and along the outer side of said secondary alley.

4. A bowling game comprising two parallel lanes lying in the same horizontal plane connected by a curved and banked lane defining a substantially true semi-circular path to which said parallel lanes are tangent, and said curved lane and one of said parallel lanes having gutters formed along a portion of the marginal edges thereof.
